US0D1031299S

(12) **United States Design Patent** (10) Patent No.: **US D1,031,299 S**
(45) Date of Patent: ** Jun. 18, 2024

(54) **SOFA**

(71) Applicant: **VidaXL IP B.V.**, Venlo (NL)

(72) Inventor: **Wouter Bakker**, Venlo (NL)

(**) Term: **15 Years**

(21) Appl. No.: **35/516,903**

(22) Filed: **Apr. 20, 2022**

(80) **Hague Agreement Data**

Int. Filing Date: **Apr. 20, 2022**

Int. Reg. No.: **DM/220365**

Int. Reg. Date: **Apr. 20, 2022**

Int. Reg. Pub. Date: **Apr. 21, 2023**

(30) **Foreign Application Priority Data**

Mar. 30, 2022 (CN) 202220736500.1

(51) **LOC (14) Cl.** **06-01**

(52) **U.S. Cl.**

USPC **D6/370**; D6/381

(58) **Field of Classification Search**

USPC D6/334, 370, 371-374, 381, 716

CPC A47C 17/02

See application file for complete search history.
